UNITED STATES PATENT OFFICE.

BRYSON D. HORTON, OF DETROIT, MICHIGAN.

ELECTRICAL SWITCH.

1,114,988.

Specification of Letters Patent. Patented Oct. 27, 1914.

Application filed April 5, 1913. Serial No. 759,005.

To all whom it may concern:

Be it known that I, BRYSON D. HORTON, a citizen of the United States, residing at Detroit, in the county of Wayne and State 5 of Michigan, have invented certain new and useful Improvements in Electrical Switches, of which the following, taken in connection with the accompanying sheets of drawings, is a full, clear, and exact description.

10 My invention more specifically relates to certain improvements in electrical switches of the "armor-clad" or "protected" type, where the switch mechanism is inclosed within a casing provided with a hinged 15 cover, which is preferably made of metal, suitable means being provided exterior of the casing for operating the switch mechanism.

My invention comprehends certain details 20 of improvements in a switch of this type, among which are to provide a new and improved form of crank or operating handle, improved means for mounting the same in the casing and attaching it to the switch 25 mechanism improved means for retaining the cover of the receptacle in its closed position, and having provision for sealing the same in this position, to prevent tampering with by unauthorized persons without detection, means whereby the cover of the casing 30 may be positively locked in closed position and finally means for locking the switch in "off" position, with the cover closed and locked when desired.

35 Referring to the accompanying drawings; Figure 1 is a plan view of a switch embodying certain of the improvements constituting my invention, the cover of the receptacle being removed. Fig. 2 is a cross sectional view on lines A—A of Fig. 1. Fig. 3 is a fragmentary detail illustrating the sealing and locking means. Figs. 4 and 5 are enlarged details in cross section showing the improved fastening means for retaining the 45 cover in its closed position, and by which means the cover may be sealed in its closed position. Fig. 6 is a top plan view showing the switch embodying my invention with the cover of the receptacle in a closed position. Fig. 7 is a cross sectional view on lines 50 B—B of Fig. 6, showing the position of the switch arm when the switch is in its "on" position and also showing in dotted lines the position it assumes when the switch has been thrown into its "off" position, the same being locked in this position by the engage-

ment of the switch arm with an abutment formed on the cover of the receptacle.

In detail, 1 indicates the body of the metal casing or housing, having a hinged cover 2. 60 3 indicates a base of insulating material upon which are mounted the switch contacts 4 and 5, and fuses 6.

7 indicates a pair of knife-switch blades connected by a cross-head 8, to which is 65 fastened a screw-eye 9, provided for the reception of the end of the crank or operating handle 10. This crank or operating handle is formed in one piece and is preferably made of cold-roll steel bent into the form 70 shown, so as to procure proper leverage and render the same capable of opening and closing the switch blades and contacts readily. In forming the operating handle or crank in one piece I produce a moving 75 switch part, which is practically indestructible by ordinary usage, and thus eliminate the liability of loosening of parts, present in switch handles of built-up construction. At the same time, I have appreciably decreased the cost of manufacture of this particular part of switch.

The crank or operating handle 10 is mounted in the side of the body of the casing, through an aperture 11, provided therein. This aperture is large enough to permit the insertion of the handle in its formed condition and in order to provide for its proper positioning, I use a split bushing, 85 consisting of like parts 12 and 13, which, 90 when combined, provide a bearing for the operating handle and also fill the space of the aperture unoccupied by the operating handle itself. The bushing projects within the casing and provides an increased bearing 95 for the handle, as well as a substantial alining member for the same.

The body of the casing is provided with a laterally extended lug 14, and the cover of the casing is provided with a similar lug 100 14, co-inciding therewith, the two meeting when the receptacle is closed. These lugs are drilled at 15 for the accommodation of the shackle of a pad-lock for locking the receptacle closed.

105 Provided on the body of the casing and preferably riveted thereto is a sheet metal plate member 16, constituting part of a fastening device, for holding the cover closed and at the same time rendering the 110 switch mechanism readily accessible. This member is provided with a circular cut-out

portion 17, for the reception of a thumb screw carried by the cover. At the lower end of the sheet metal member is provided a laterally extending perforated ear 18, the object of which will be presently understood.

19 indicates the thumb screw carried by the cover of the receptacle and has an enlargement 20, adapted to fit and occupy 10 snugly the circular cut-out portion 17 of the sheet metal plate 16 when the cover is in its closed position, and the former is screwed home, thus preventing the opening of the cover. The head or finger piece of the 15 thumb screw is perforated at 21 and through this perforation as well as perforation of the ear 18, is inserted a flexible wire 22 carrying a suitable seal 23 serving to seal the cover in its closed position to protect it 20 from being tampered with without detection.

Referring now in detail to Fig. 7, 24 indicates a depending fin or abutment cast integral with the cover, which is designed 25 to engage a part of the crank or operating handle 10 within the casing, so that when the handle has been thrown over to the extreme length of its oscillation and the cover is closed, the handle is locked in this 30 position so that it would be impossible to move the handle to close the switch without first unlocking and opening the cover to permit the handle to pass the abutment. By this means I am able to positively lock 35 the switch mechanism in its off position to prevent unauthorized manipulation.

I do not wish to be understood as limiting myself to the precise structure shown and described as the same may be varied 40 and departed from and still be within the spirit and scope of my invention as set forth in the appended claims.

Having thus described my invention, what I claim as new herein and desire to 45 secure by Letters Patent is:

1. A switch of the character described, including a casing provided with a cover, a switch mechanism therein, said switch mechanism including stationary and movable 50 contacts and a crank for operating the switch, said cover being provided with a cavity for permitting a partial movement of the crank to open the switch without opening the cover, means carried by the cover adapted to be brought into engagement with the crank after the latter has been moved to its full opened position when the cover is open said means engaging the crank when in this position upon the closing 55 of the cover.

2. A switch of the character described, including a casing having a cover, a switch mechanism therein, said switch mechanism including stationary and movable contacts 60 and a crank for operating the movable con-

tacts, said cover being provided with a cavity for permitting a partial movement of the crank to open the switch without opening the cover, an abutment carried by the cover and projecting into the cavity, and adapted to be brought into engagement with the crank after the latter has been moved to its full open position when the cover is open said abutment engaging the crank when in this position upon the closing 75 of the cover.

3. A switch of the character described, including a casing having a cover, a switch mechanism therein, said switch mechanism including stationary and movable contacts, a crank for operating the movable contacts, said cover being provided with a cavity for permitting a partial movement of the crank to open the switch without opening the cover, means carried by the cover adapted to be brought into engagement with the crank after the latter has been moved to its full opened position when the cover is open said means coöperating with the crank when in this position and when the cover 90 is closed, and means for locking the cover closed.

4. A switch of the character described, including a casing provided with a hinged cover, a switch mechanism therein, said switch mechanism including stationary and movable contacts, a crank operating member operably associated with the movable contacts, said cover being provided with a cavity to permit of the opening of the switch 100 without opening the cover, means carried by the cover and projecting into the cavity for engaging the switch mechanism in open position for holding the same in this position when the cover is closed, and independently operated means for locking the cover in closed position to lock the switch mechanism in open position.

5. In a switch of the character described including a casing provided with a hinged 110 cover, a switch mechanism within said casing, including stationary and movable contacts, an operating handle mounted in the body of the casing and operably connected with the movable contacts and adapted to move them to make or break an electrical circuit, a lug formed integral with the cover of the casing adapted to engage the switch handle positively to hold the switch open after the same has been thrown to its extreme limit of its circuit breaking movement when the cover is open, said lug engaging the handle when the cover is thereafter closed for retaining the switch mechanism in its full open position and means 115 for positively locking the cover closed to prevent the establishment of an electrical circuit through the contacts.

6. A switch of the character described 120 including a casing provided with a hinged 125

cover, said cover being provided with a cavity, a switch mechanism within said casing including stationary and movable contacts, an operating handle mounted in the body 5 of the casing adapted to move the movable contacts to make and break the electrical circuit, means comprising an abutment projecting into the cavity adapted to cooperate with the handle, said switch handle adapted to impart to said movable contacts, a partial circuit breaking movement when the cover is closed and a full circuit breaking movement when the cover is 10 open, said abutment adapted to engage the handle after the cover is open, the said handle thrown to its extreme circuit breaking position and the cover thereafter closed, to prevent the movement of said handle.

7. In a switch of the armor clad type, an 15 apertured casing, an operating handle, said

operating handle being formed in one piece and provided with a substantially U-shaped portion adapted when in its formed condition, to be inserted through the aperture of the casing, said U-shaped portion 20 having its parallel opposite U-arms substantially parallel with the sides of the casing when the operating arm is in position and a two part bushing adapted when assembled to surround the handle, close the 25 aperture and serve as a bearing and alining member for said handle.

In witness whereof I have hereunto set my hand in the presence of two subscribing witnesses this second day of April, 1913. 30 35

BRYSON D. HORTON.
